PICK SHAFTS FOR LOOMS

Lloyd George Urquhart, Westboro, Mass., assignor to
H. F. Livermore Corporation, Boston, Mass., a corpora-
tion of Delaware

Filed Oct. 12, 1959, Ser. No. 845,839

5 Claims. (Cl. 139—147)

This invention relates to looms, and in particular to the pick shafts thereof which transmit motion derived from the loom cam shaft to the pickersticks which pick the shuttle back and forth across the loom.

These pick shafts are subjected to probably the most violent forces of any parts of the loom, and hence break with annoying frequency, having an average life of about three weeks in the conventional Crompton and Knowles looms. They are actuated in one direction of their rocking movement by the impact of the rapidly traveling pick ball against the pick cam bolted on the pick shaft. The force of the blow is delivered to the cam closely alongside of and at right angles to the pick shaft, and results in a powerful combined deflecting force and torque exerted on the pick shaft. Since in these worsted looms the pick shaft is made angular in section, in order to fit the pick cam and sweep arm thereon non-rotatably, this force stresses and fatigues the metal at one "corner" of the rectangular section, causing a fracture which speedily spreads across the shaft and results in its breakage usually close to the forward end of the rectangular hub of the pick cam on which the blow falls.

While longer pick shaft life could doubtless be attained by using a shaft of round section, this resort is not practicable because all the mills using these looms are stocked up with a supply of parts designed to fit only upon pick shafts of rectangular section, which alone are provided by the loom builder.

These shafts are always made in one piece with a journal of several inches in length formed on each end and received respectively in a sleeve bearing forming an integral part of a bracket bolted to the inward surface of the loom side. When the shaft breaks, both broken halves of the broken shaft of course have to be removed, together with their fittings, namely the pick cam, the sweep arm, and the shuttle ejector arm. This can only be done by unbolting and removing one of the brackets having the pick shaft bearings, because the broken ends of the shaft cannot be otherwise disaligned far enough to slide either of the broken halves out of its bearing in the bracket. Both of these brackets are inaccessible until the cloth roll is removed, after which the loom fixer can get at the bracket carrying the bearing adjacent the sweep arm, at the end of the pick shaft nearer the front of the loom, by lying on his back under the loom, in a position where he is at risk of injury by the fall of the cloth roll, often heavily loaded, which must be laid on top of the breast beam for lack of any other resting place during this operation.

Apart from the cost of the new pick shaft, the job of replacement of the shaft and applying and adjusting the fittings takes at least $\frac{3}{4}$ of an hour, during which period the loom is of course out of use, a serious economic loss when costly worsted fabrics are being produced.

The present invention aims to provide means for use in existing looms and usable with the conventional fittings regularly used and on hand in the mills, which is adapted to save time, effort, cost and hazard of bodily injury in repairing a broken pick shaft.

To these ends, the invention provides a two-piece or divided pick shaft of which the two component members or halves are joined to rock in unison by a coupling. This coupling, of split sleeve type, is long enough to embrace the two halves throughout the major portion of the inter-

2

val between the pick cam and the sweep arm, thus enabling the adjacent ends of the interrupted shaft, when the journal on each half is in place in its respective bearing, to be separated by a gap longer than either journal. When either half of the two-piece pick shaft breaks in use, the coupling can be loosened and slid along the unbroken half far enough to expel or permit removal of the broken portion of the other half within the coupling while the remainder of such broken half stays in its bearing, whereupon such remainder is withdrawn from its bearing without interference. The broken half is then replaced by a new half shaft after transfer of the fitting thereto, by merely sliding its journal into its bearing, all by reaching through the openings available in the loom side and without disturbing the cloth roll.

As will be obvious, the same type of rectangular section pick shaft and fittings is retained, while the coupling bridging the gap between the ends serves to transmit the torque, braces the mid-length portion of the shaft assembly against the deflection caused by the pick ball's blow, a feature lacking in the prior one-piece shafts, and by the same token gives more uniform picking by preventing whipping (twisting) of the pick shaft, and saves in the cost of parts because only half of the shaft has to be replaced, in addition to providing quick, easy and safe repair of the damage.

Other objects of the invention, and the manner of their attainment, are as made plain hereinafter.

An illustrative embodiment of the invention is shown in the accompanying drawings, in which

FIG. 1 is a perspective view of the parts comprising the pick motion of the loom, with omission of certain supporting and driving members.

FIG. 2 is a perspective view on a larger scale showing the novel two-part pick shaft with its coupling, but with the pick cam, sweep arm and shuttle ejector arm omitted.

The parts of FIG. 1, with the exception of the novel pick shaft 1, are those of the pick motion of the conventional Crompton and Knowles worsted loom. It comprises a cam shaft 3 driven in usual manner and carrying thereon a pick ball or tappet 5 rotatably mounted on the end of an arm 7 fixed on the cam shaft 3, the pick ball in its orbit around the cam shaft striking the concave surface of a pick cam 9 fixed by means of its rectangular hub and clamping screws 11 on the rear half 13 of divided pick shaft 1. On the forward half 15 of the pick shaft is fixed a sweep arm 17 by means of its hub 19 and clamping screws 21, and also a shuttle ejector arm 23 with its hub 25 likewise bolted to the shaft. When the pick shaft is rocked counterclockwise by the pick ball 5 striking cam 9, sweep arm 17 jerks the pickerstick 25' sharply toward the center of the loom to throw the shuttle (not shown), through the medium of a lug strap 27 and connector 29. Shuttle ejector arm 23 is actuated by a treadle 31 when it is desired to get the shuttle out of the box (not shown) without starting the loom.

In accordance with the invention, pick shaft 1 is made in two halves 13, 15, as noted, though they are not necessarily of equal length. Each is rectangular in section, and provided on one end with a journal 33, 35 to be received respectively in the bearings provided as integral parts of the original brackets 37, 39, which as usual are bolted to the inward face of the loom frame (not shown). The combined length of the rectangular portions of the two halves 13, 15, is less than the distance between the bearings in these brackets by an amount exceeding the length of either journal 33, 35, which makes it possible to insert the journal of either half of the pick shaft 1 into its proper bearing and then do the same with the other half, without disturbing the fastenings of either bracket 37, 39. That is, the gap provided between the adjacent ends 14 and 16 of the two halves when in place in the

loom permits the axial alignment of the two halves with each other and with their bearings as needed to enter the journal of the second half into its bearing, after the first half is in place. This would be impossible without unbolting one bracket 37, 39, if the confronting ends of the two halves overlapped as the second journal is presented to its bearing.

To join the mutually adjacent end portions of the two halves 13, 15 of the pick shaft, a two-part coupling 41 is provided, each part having a right dihedral internal angle 43 whose sides are of less extent than the width of that face of shaft 1 which they respectively engage, and having integral flanges 45 extending in a common plane at both sides of shaft 1 and equipped with holes 49 through which are put a plurality, herein four, of bolts 47 provided with nuts.

This coupling 41 is made as long in axial extent as possible, for its bracing effect explained later herein, and for this purpose the forward half 15 of the shaft is made longer, while the rearward half 13, more prone to break, is made shorter, than its companion piece. Normally the coupling 41 will match the length of the part 15 measured from the hub of the closest fitting (herein the sweep arm) to its rearward end 16. Thus in installing a replacement for a broken rear half shaft 13 the clamping bolts 47 are merely loosened and the coupling then slid forward along the shaft 15 up to such fitting, leaving ample clearance for the forward end 14 of a replacement part 13 in aligning its journal 33 with its bearing in bracket 37 so as to insert it therein.

Once the novel pick shaft is installed, replacement of a broken half is very quick and simple. It is of course necessary to remove the original one-piece type of pick shaft following breakage thereof by the familiar and troublesome method of removing the forward bearing bracket 39, since the journals in the bearings prevent disalignment and withdrawal of the broken parts so long as the bearing brackets remain fixed. Thereafter, the forward bracket 39 is bolted in place, the sweep arm and shuttle ejector arm are transferred to the forward half 15 of the improved divided pick shaft, and the journal 35 of this half shaft is inserted in its bearing in bracket 39. With coupling 41 loose on shaft 15 and slid forward to its limit, the rearward half shaft 13 is then equipped with the pick cam 9 taken from the old shaft and slid into place in its bearing in rear bracket 37, and the coupling 41 slid rearward so that it embraces equal lengths of the adjacent end portions of half shafts 13 and 15, bridging the gap left between them after their journals are thrust home into their respective bearings. Bolts 47 are then tightened, whereupon the pick shaft is in readiness for resuming its work. The slot between the opposing flanges 45 of the two portions of the coupling 41 permits observation of the position of the shaft ends therein, and guide marks in the form of notches 51 on the edge of one flange 45, to be aligned with the respective shaft ends, are provided to indicate the correct relative positions of the shaft halves and the coupling.

The coupling 41 which bridges the gap and connects the two halves of the shaft to rock in unison not only transmits the torque from the cam-driven rear half to the front half which actuates the sweep arm, but by its prolonged axial extent serves to brace the shaft against the bending tendency caused by the pick ball's blow delivered at right angles to the shaft's axis. Because it further stiffens the shaft in its resistance to twisting or "whipping," it thus gives more uniform picking of the shuttle. The novel device further saves in cost of repair parts, since

the rear half 13 is nearly always the part that breaks, and it costs less than one-third that of the full-length one-piece prior shaft.

But the main economy is that noted at the outset herein, in that it provides quick and easy repair of a broken pick shaft, in that only one-half of the shaft must be replaced, and therefore only the fitting or fittings on such half need be transferred to the replacement, which is then put in place, all without the necessity of removing the cloth roll and the forward bracket and subsequently returning them to their places. The whole operation is easily performed in 15 minutes as against about $\frac{3}{4}$ of an hour with the prior one-piece shaft. The saving of $\frac{2}{3}$ of the time the loom was put out of production in prior practice thus easily pays the cost of the entire novel structure in a single pick shaft repair when the loom is weaving worsted suitings or similar medium to high cost fabrics.

A similar economy is attained when a worn or broken pick cam or sweep arm must be replaced, or when as is sometimes required the pick cam must be changed to adapt the loom to the weaving of different kinds of goods.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but what I do claim is:

1. Picking mechanism for looms comprising in combination bearings in fixed spaced relation to each other, a shaft member having an integral journal on one end mounted in one bearing, a pick cam fixed on such shaft member, a second shaft member having an integral journal on one end mounted in the other bearing, a sweep arm fixed on the second shaft member, and means coupling the two shaft members together to turn in unison and holding them in coaxial relation and spaced apart by a distance as great as the length of a journal on one of the shaft members.
2. In combination, a two-piece pick shaft of angular section, a pick cam fixed on one such piece, means actuating the pick cam, a sweep arm fixed on the other such piece, means coupling the two pieces together in spaced coaxial relation comprising members each having a dihedral angle engaging two faces of the angular section of each piece, and means drawing the members together and clamping them against the said faces of the shaft.
3. The combination according to claim 2 in which the axial length of the coupling means substantially equals the extent of one shaft piece from the sweep arm thereon to its end within the coupling means.
4. A pick shaft for looms comprising in combination two shaft members of angular section each having an integral journal on one of its ends, and a coupling engaging the other end-portions of both shaft members, holding the two shaft members in coaxial relation to each other and against relative rotation and spaced apart by a distance as great as the length of a journal on one of the shaft members.
5. The combination according to claim 4 in which the coupling is slidable for substantially its length along one shaft member.
